HANDLE

Stanley F. Korol, Mansfield, Ohio, assignor to Borg-Warner Corporation, Chicago, Ill., a corporation of Delaware

Filed July 16, 1969, Ser. No. 18,233

Term of patent 14 years

Int. Cl. D23—01; D8—03
U.S. Cl. D23—29

FIG. 2

FIG. 3

FIG. 4

FIG. 1 is a top plan view of the handle of this invention;

FIG. 2 is a front elevational view thereof;

FIG. 3 is a side elevational view of the left side thereof; and

FIG. 4 is an elevation view of the right side thereof.

The fragmentary broken line representation is for purposes of illustration only.

I claim:

The ornamental design for a handle, substantially as shown and described.
